United States Patent

Des. 238,300
Patented Dec. 30, 1975

238,300

BANQUET CABINET

Richard O. Klemm, Crystal Lake, Ill., assignor to Food
Warming Equipment Company, Inc., Elk Grove Village,
Ill.

Filed Apr. 8, 1974, Ser. No. 459,089

Term of patent 14 years

Int. Cl. D12—02; D15—08
U.S. Cl. D55—1 E

FIG-4FIG-5FIG-6FIG. 1 is a left front perspective view of a banquet cabinet showing my new design;

FIG. 2 is a front elevation view thereof;

FIG. 3 is a left side elevation view thereof;

FIG. 4 is a top plan view thereof;

FIG. 5 is a rear elevation view thereof; and

FIG. 6 is a bottom plan view thereof.

The right side of the banquet cabinet is substantially flat and unornamental.

I claim:

The ornamental design for a banquet cabinet, substantially as shown and described.
